DIE CUSHION ARRANGEMENT FOR PRESSES

Walter Ernst, Dayton, Ohio, assignor to The Commonwealth Engineering Company of Ohio, Dayton, Ohio, a corporation of Ohio

Original application September 15, 1949, Serial No. 115,901. Divided and this application November 2, 1950, Serial No. 193,645

5 Claims. (Cl. 113—45)

1

This invention relates to presses and to die cushion arrangements therefor and is a division of my copending application Serial Number 115,901, filed September 15, 1949, and assigned to the same assignee as the instant application.

Die cushion arrangements are often employed in connection with presses, both mechanical and hydraulic, especially where a workpiece is to be drawn. A die cushion is useful in such circumstances in that it forms a resilient support for the article being drawn that prevents it from becoming torn or wrinkled as the drawing proceeds.

A die cushion thus constitutes generally a platen or a plunger to which a platen can be attached, and some arrangement for resisting movement of the platen or plunger so that a predetermined cushioning force can be exerted on the work member during the drawing operation.

Die cushions of this nature are also useful as ejectors for assisting in removing the workpiece after it has been drawn, and when functioning in this manner, may either follow the forming tool upwardly as it retracts after a drawing operation, or may move upwardly to eject the workpiece after the drawing tool has been retracted.

Ordinarily, die cushions of the type referred to are integrally associated with the press with which they are to be used at the time the press is manufactured, and thus form a permanent and inseparable part of the press. This is particularly true where the press is of any substantial size, say from five hundred tons to twenty-five hundred tons capacity.

It has been customary in the past in connection with presses of this type to order a press having a die cushion with the thought in mind that the principal utility of the press would be for drawing workpieces. Inasmuch as a die cushion, particularly one of the larger size, is an expensive auxiliary, presses having die cushions were substantially more expensive than ordinary presses. Accordingly, when a die cushion press of this nature was utilized for other work operations which did not require a die cushion, a much more expensive tool was being used than the job justified.

With a die cushion mounted integrally in a press frame, or so mounted as to be difficult to remove, the utility of the press was further limited in that the space occupied by the die cushion was not available for any useful purpose.

The instant invention proposes an arrangement for a die cushion in a press such that the die cushion can be readily added to the press or readily removed from the press at any time in order to convert the press from standard to die cushion operation at will.

2

The die cushion, readily detachable from the press, can be offered for sale as a separate item, and only purchased when the job requirements justify it. Furthermore, the die cushion can readily be removed from the press and transferred to another if desired, and in this manner effect a substantial saving in the amount of investment necessary in order to provide a range of press capacities for various jobs.

This invention also provides improved control means for a die cushion of the nature referred to, whereby the die cushion can selectively operate on a plurality of different types of cycles, such as the one where it immediately follows the drawing tool upwardly and the one where the upward movement of the die cushion is delayed until after the drawing tool has retracted.

The advantages referred to above, as well as other advantages will become more apparent upon reference to the following description, taken in connection with the accompanying drawings, in which:

Figure 1 is a front elevational view of a hydraulic press embodying the die cushion structure according to my invention;

Figure 2 is a vertical section through the lower part of the press showing somewhat more in detail the construction of the die cushion;

Figure 3 is a plan section indicated by line 3—3 on Figure 2;

Figure 4 is a plan section indicated by line 4—4 on Figure 2;

Figure 5 is a view indicated by line 5—5 on Figure 2;

Figure 6 is a view similar to Figure 5 but showing a somewhat modified arrangement of the die cushion of this invention; and

Figure 7 is a fragmentary view showing one of the valves forming a part of the operating circuit for the die cushion.

Referring to the drawings somewhat more in detail, the press shown in Figure 1 comprises the usual head 10 and bed 12, spaced apart by the uprights 14, which enclose strain rods 16 having the nuts 18 which retain the head, bed, and uprights clamped together.

The uprights serve to guide a platen 20 that may be powered by a ram 22 extending into the press head where it is connected with a double acting piston that can be acted on by fluid pressure to move the platen toward or away from bed 12.

A blankholder platen may be suspended from main platen 20, as by rods 26, and is adapted for actuation by rods 28 which extend into the bed for connection to beams 29 that have thereon the pistons 30 in the cylinders 32. Cylinders

32 are fixed in bed 12 and are adapted for receiving fluid pressure via the flexible conduits 34 in the manner more fully disclosed in my application Serial Number 115,901, identified above.

The press bed 12 is preferably a cast member and includes a substantially rectangular center opening 36, as will be best seen in Figures 2, 3, and 4. This central opening is utilized for receiving the die cushion or ejector unit according to this invention.

One type of die cushion unit is illustrated in Figure 2, and comprises a single acting plunger connected to the die cushion platen. This die cushion is adapted for relatively light service, as when the press is equipped with a blankholder.

A somewhat different die cushion arrangement is illustrated in Figure 6, wherein the die cushion platen is connected with a double acting plunger. This die cushion is adapted for somewhat heavier service and may be employed when a press is not equipped with a blankholder, but instead utilizes a draw ring in association with the drawing die to obtain a blankholder action. The difference between the two die cushion arrangements is, therefore, one of degree and not of kind.

For detachably receiving the die cushion or ejector assembly, the press bed has the upstanding bored bosses 38 through which the strain rods 40 can be passed for supporting the beams 42 that extend from the front to the back of the press and on the underneath side of the bed. These beams are adapted for receiving the projecting parts 44 of the die cushion or ejector cylinder 48 which reciprocably receives a plunger 50 on the upper end of which is mounted a platen 52. Platen 52 is adapted for being guided in its reciprocatory movements by the guide rails 54 mounted on the faces of ribs about the cavity 36.

It will be understood that usually there is a bolster plate resting on the upper surface of the press bed and that the platen 52 will normally bottom against the underneath side of the said bolster plate. In the manufacture of the press, the press bed is always formed with the rectangular opening 36 extending therethrough and with the upstanding bored bosses 38, so that at any time it is desired to do so, the die cushion or ejector assembly can be mounted in the press or removed therefrom. The illustrated arrangement permits this to be done in a minimum of time and at a minimum of expense. The die cushion assembly is removed simply by disconnecting the hydraulic lines thereto, taking the nuts off one end of the strain rods 40, and lowering the assembly into a pit beneath the press.

The die cushion arrangement of Figure 2 and that of Figure 6 have in common the feature of a check valve connected with the cylinder to raise the die cushion platen. In each case, the check valve is by-passed by a relief valve opening away from the cylinder so the die cushion platen will yield at a predetermined thrust and means are provided for locking the check valve closed to delay the upward movement of the die cushion platen, if so desired.

In Figure 2, the die cushion ram is single acting in its cylinder, whereas in Figure 6, the die cushion plunger 50 is double acting by means of a piston 56 which closely fits in bore 58 of the die cushion cylinder 48.

The upper and lower ends of bore 58 are interconnected by passage 60 which has therein the check valve 62 adjacent the lower end of the cylinder and which is by-passed by relief valve 75

64. In operation, when the die cushion platen 52 is urged downwardly by the action of the press, the fluid from beneath piston 56 is forced through relief valve 64 and this generates the required pressure action upwardly on the piston.

Part of the fluid displaced from the lower end of bore 58 passes to the upper end thereof through passage 60, and the remainder passes through conduit 66 to the flange fitting 68 mounted on the 10 side of the press head and which is connected to the pushback side of the press plunger 22.

When the pressing operation of the press is complete and the main platen of the press commences to move upwardly, pressure is supplied 15 to flange fitting 68 to pass therefrom to the pushback side of the press plunger 22 and into conduit 66. At this time the die cushion platen 52 may follow the main press platen upwardly or may be delayed in its return.

20 This is accomplished by the valving arrangement shown in Figures 6 and 7. The check valve 62 normally yields to pressure standing on its upper face in passage 60, but may be held stationary by an auxiliary piston 70 which is adapted for being moved upwardly against the bottom of the check valve member by pressure conducted thereto through conduit 72. Conduit 72 is connected with conduit 66 through a three-way valve 74 that also includes an exhaust line 76 30 and a movable valve member 78.

Valve member 78 is normally urged by a spring 80 into position to connect the lower branch of conduit 72 leading to auxiliary piston 70 with solenoid S2 by closure of limit switch LS2 by 35 a cam 82 on the press platen 20 will move valve member 78 into the position shown, wherein conduit 72 establishes a continuous passage from auxiliary piston 70 to conduit 66. With the valve member so shifted, the pressure supply to 40 the pushback side of the press plunger 22 to raise the press platen will also act on auxiliary piston 70 and clamp check valve 62 closed, thereby preventing upward movement of the die cushion platen.

45 When the press platen has moved far enough to release limit switch LS2, solenoid S2 is de-energized, spring 80 is again effective to connect the branch of conduit 72 leading to auxiliary piston 70 with exhaust conduit 76, and check 50 valve 62 is then free to open under the pressure in passage 60 and to bring about upward movement of the die cushion plunger and platen.

It is to be noted that the die cushion plunger 50 and piston 56 are so designed that the cross-sectional area of plunger 50 is sufficient to bring about upward movement of the plunger and platen when check valve 62 is open, and that piston 56 is of such a size that the necessary thrust is exerted thereon to give the proper die cushion action.

Then, by means of the interconnecting passage 60, the only fluid that it is ever necessary to supply to the die cushion unit through the conduit 66, or to convey away from the die cushion 65 unit, is the amount of fluid displaced by the plunger 50 as it reciprocates in the cylinder 48. A relatively small conduit can be utilized for conveying this amount of fluid and the arrangement represents a definite economy of piping.

Operation

In operation the press is operated by reciprocating the main platen 20 by a reversible supply of pressure fluid to the main press plunger 22 in any of several well-known manners, it be-

ing understood that the press could operate on manual cycle, semi-automatic, or full-automatic, as desired.

Where the type of work being done makes it advisable, the press is provided with a die cushion in the manner previously described. Thus, if the press is to be operated with the die cushion, die cushion action is had when the work is engaged by the platen and moved downwardly so as to move die cushion platen 52 downwardly. When the die cushion platen is so moved, the accompanying downward movement of plunger 50 and piston 56 is resisted by the setting of relief valve 64.

Prior to the completion of the pressing stroke, 15 cam 82 on platen 20 actuates switch LS2, thereby energizing S2 and moving valve member 78 into position to connect conduit 66 with conduit 72. Then, when the press platen starts up and the supply of fluid to the pushback side of the press ram is conveyed through conduit 66 to passage 60, it is also conveyed through 20 conduit 72 to auxiliary piston 70 which moves upwardly and clamps check valve 62 closed. This prevents upward movement of the die cushion 25 piston, ram, and platen.

However, when cam 82 runs off switch LS2, valve member 78 shifts to exhaust conduit 72 thereby releasing auxiliary piston 70 and check 30 valve member 62 so that pressure in passage 60 can act on both faces of piston 56 and urge it upwardly together with plunger 50 and die cushion platen 52.

The valve 74 may, of course, be made inoperative by opening switch 90, so that die cushion 35 platen 72 will follow the main platen upwardly immediately, if so desired.

From the foregoing, it will be seen that the press of this invention can be a simple assembly 40 consisting of the press frame with the main press platen and the actuating mechanism therefor, or that the same press can be equipped with a die cushion and operate as a die cushion press for carrying out certain types of work.

The addition of the die cushion does not require the addition of any more hydraulic horsepower and imposes no load on the press frame except a certain amount of mechanical loading on the bottom of the bed which in no way detracts from the structural strength of the press frame, 45 because this portion of the frame is never loaded to a critical degree during operation of the press.

It will be understood that this invention is susceptible to modification in order to adapt it to different usages and conditions, and, accordingly, it is desired to comprehend such modifications within this invention as may fall within the scope of the appended claims.

I claim:

1. In a hydraulic press having a main platen and a die cushion platen; said main platen having fluid operable advancing and retracting means, a double acting plunger having its rod end connected with said die cushion platen, a cylinder in which said plunger is reciprocable, a 60 passage in the cylinder connecting the opposite ends thereof, a check valve in said passage having its inlet toward the rod end of said cylinder and its outlet toward the other end of said cylinder, a relief valve bypassing said check valve and responsive to a predetermined pressure at 65 said outlet for permitting fluid to flow from the outlet to the inlet thereof, means hydraulically connecting the inlet of said check valve with said fluid operable retracting means for the said 70 75

main platen for fluid flow therebetween in both directions, a clamping piston associated with said check valve responsive to fluid pressure for clamping said check valve in its closed position, said piston having a greater effective area than the area of the check valve that is exposed to the pressure at the inlet thereof when the check valve is closed, and means for selectively connecting said piston with said fluid operable retracting means for holding said plunger stationary during a supply of pressure to said fluid operable retracting means.

2. An arrangement as set forth in claim 1 in which the last-mentioned means comprises a valve between said piston and said fluid operable retracting means normally positioned for connecting said piston with exhaust, electrical means energizable for shifting said valve to connect said piston with said fluid operable retracting means, a switch for energizing said electrical means, and a cam carried by said main platen operable for engaging and closing said switch when the main platen is adjacent its fully advanced position.

3. In a die cushion arrangement of the type described; a cylinder, a plunger extending into said cylinder, relief valve means connected with said cylinder for resisting the discharge of fluid therefrom thereby to resist movement of the plunger into said cylinder, a supply of pressure fluid, a check valve connecting said supply with said cylinder and opening toward the cylinder, said check valve comprising a valve body having a bore, a check valve member reciprocable in said bore from a seated position where the bore is closed to a position where the bore is open for the passage of fluid, said valve member when seated presenting a predetermined area to pressure fluid supplied to the inlet of the valve, an auxiliary piston in said bore on the opposite side of said valve member from the seat of the valve, and means selectively operable for supplying pressure fluid to the side of said piston opposite said valve member for clamping said valve member in its seated position, said piston having an area greater than said predetermined area of the valve member whereby a supply of fluid at any pressure to both the inlet of the check valve and the auxiliary piston will clamp the valve closed.

4. In a die cushion arrangement of the type described; a cylinder, a plunger extending into said cylinder, relief valve means connected with said cylinder for resisting the discharge of fluid therefrom thereby to resist movement of the plunger into said cylinder, a supply of pressure fluid, a check valve connecting said supply with said cylinder and opening toward the cylinder, said check valve comprising a valve body having a bore, a check valve member reciprocable in said bore from a seated position where the bore is closed to a position where the bore is open for the passage of fluid, said valve member in seated position presenting a predetermined area to pressure fluid delivered to the inlet of the valve, an auxiliary piston in said bore on the side of said valve member toward which the valve member moves toward bore opening position, said piston having a greater area than said predetermined area of said valve member, means normally connecting the bore on the side of the piston opposite said valve member with exhaust, and means selectively operable for connecting the said side of the piston with the inlet side of said check valve whereby the supply of pressure fluid to the said inlet will cause said auxiliary piston to

clamp the valve member in its bore closing position.

5. In a hydraulic press having a main platen and a die cushion platen; said main platen having fluid operable advancing and retracting means, a double acting plunger having its rod end connected with said die cushion platen, a cylinder in which said plunger is reciprocable, a passage in the cylinder connecting the opposite ends thereof, a check valve in said passage having its inlet toward the rod end of said cylinder and its outlet toward the other end of said cylinder, means associated with said check valve responsive to a predetermined pressure at the outlet thereof for permitting fluid to flow from the outlet to the inlet thereof when said plunger moves during a working stroke of said main platen, means hydraulically connecting the inlet of said check valve with said fluid operable retracting means for the said main platen for the exchange of fluid therebetween in both directions so that, normally, said check valve will be opened by the pressure fluid supplied to said fluid operable retracting means for the main platen whereby said plunger will be urged upwardly upon a supply of pressure fluid to said fluid operable retracting means simultaneously

10
15
20
25

with the upward travel of the main platen, fluid actuated means associated with said check valve responsive to fluid pressure for preventing opening of said check valve for holding said plunger stationary when the main platen retracts upon a supply of pressure fluid to said fluid operable retracting means, and means selectively operable for supplying pressure fluid to the said fluid actuated means associated with said check valve during the initial retracting movement of said platen.
